US00D672519S

(12) **United States Design Patent**
Kandasamy et al.

(10) **Patent No.:** **US D672,519 S**
(45) **Date of Patent:** **** Dec. 11, 2012**

(54) **SPRAY MOP HOUSING**

(75) Inventors: **Balaji Kandasamy**, Naperville, IL (US);
Joseph Seifts, Naperville, IL (US)

(73) Assignee: **Freudenberg Household Products LP**,
Aurora, IL (US)

(**) Term: **14 Years**

(21) Appl. No.: **29/420,836**

(22) Filed: **May 14, 2012**

Related U.S. Application Data

(62) Division of application No. 29/386,799, filed on Mar. 4, 2011, now Pat. No. Des. 661,442.

CLAIM

The ornamental design for a spray mop housing, as shown and described.

DESCRIPTION

FIG. 1 is a perspective view taken from the top, front, and right side of a spray mop housing showing our new design; FIG. 2 is a top plan view of the spray mop housing shown in FIG. 1;

FIG. 3 is a bottom view of the spray mop housing shown in FIG. 1;

FIG. 4 is a front elevational view of the spray mop housing shown in FIG. 1;

FIG. 5 is a rear elevational view of the spray mop housing shown in FIG. 1;

FIG. 6 is a left elevational side view of the spray mop housing shown in FIG. 1; and,

FIG. 7 is a right elevational side view of the spray mop housing shown in FIG. 1.

The broken lines are for illustration purposes only and form no part of the claimed design.

1 Claim, 5 Drawing Sheets
